UNITED STATES PATENT OFFICE.

THEODORE M. PRUDDEN, OF HINGHAM, MASSACHUSETTS, ASSIGNOR TO KALIX CUP COMPANY, OF BOSTON, MASSACHUSETTS, A CORPORATION OF MASSACHUSETTS.

CUP-DISPENSING MACHINE.

Application filed May 18, 1925. Serial No. 30,989.

In the dispensing of paper cups the most desirable presentation is from the bottom of a nested stack in which the cups are sanitarily enclosed and supported by the bottom cup and only the bottom of the lower cup exposed so that it can be seized and withdrawn.

A great variety of mechanisms have been devised for releasing this bottom cup while catching and holding the next cup so as to support it and through it the rest of the column.

These mechanisms are usually expensive and are liable to get out of order at just the time when their service is most needed as in rush hours, thereby causing delay for repairs and loss of business.

My invention eliminates the necessity for moving parts by providing a fixed stop or stops which support the cup rim but permit passage by making a tiny incision which is thereafter almost undetectable.

As illustrative of my invention I have shown in the accompanying drawings a form of dispenser embodying my invention in simple form and well adapted to practical use. To identify the corresponding parts, conventional reference characters are employed. The views are as follows:

Fig. 1 is a vertical section through the discharge end of such a device showing the cup stack in elevation.

Fig. 2 is a fragmentary view showing the lower cup in the first stage of withdrawal.

Fig. 3 illustrates the first cup as released and the next supported.

Fig. 4 is a fragmentary plan of a cup lip supported, and

Fig. 5 is the same being released.

The cup tube 1 has its lower end fitted within and supported by a nozzle member 2, having a delivery mouth 3. At one or more points lugs 6 are struck from the back of the nozzle 2. To the lugs 6 are detachably secured by screws or pins 7 a corner of a thin two-edged blade 5. This may very conveniently, as shown, be similar to a half of one of the popular thin safety razor blades now on the market.

The pins 7 hold the blade properly positioned on an incline with any corner presented inwardly so as to just support the rim 8 of a cup C placed thereon.

When it is desired to use a cup C, the lower portion of the bottom cup is grasped and simply pulled down. In so doing the

rolled rim of the cup C, is neatly incised as at 8¹ (Fig. 5) and the cup rim passes the blade corner or corners so that it can be withdrawn and the next cup supported as in Figs. 3 and 4.

The cups may each be withdrawn in turn, being fed by gravity most conveniently. In filling it is only necessary not to drop the cup column too violently on the supporting blades since while they will support the usual column without cutting, they are apt if sharp, to cut through the bottom cup of a column if dropped so as to give any considerable impact.

My invention is capable of varied application and design, but is presented in simple form as best disclosing the invention while giving a practical device of immediate value.

All variants, modifications and substitution of parts are to be understood as within the purview of my invention if within the limits of the appended claims.

What I therefore claim and desire to secure by Letters Patent is:

1. In combination, a magazine adapted to confine a nested column of flanged top paper containers in such position as to permit successively the outermost container in the column to be grasped and withdrawn singly from the column, and a stop mounted adjacent the delivery end of the magazine and presenting an incising edge projecting into the path of withdrawing movement of the containers whereby to engage the flanged top of the contacting container in the column and prevent accidental withdrawal thereof, said stop effective when the terminal container is grasped and positively withdrawn from the column to incise the flanged top of said container and thus permit its passage therewith and immediately to engage the flanged top of the next outermost container in the column whereby again to maintain the containers in columnar assembly.

2. In combination, a magazine adapted to confine a nested column of flanged top paper containers in such position as to permit successively the lowermost container in the column to be grasped and withdrawn singly from below, and a pair of oppositely disposed stops mounted adjacent the delivery end of the magazine and presenting incising edges projecting into the path of descent of the containers whereby to engage the flanged

top of the contacting container in the column and support the column against accidental release, said stops effective when the terminal container is grasped from below and positively withdrawn from the column to incise the flanged top of the container next above in the column whereby again to support the column.

3. In combination, a magazine adapted to 10 confine a column of incisable articles to be dispensed in such position as to permit successively the terminal article of the column to be grasped and withdrawn singly, and a relatively thin blade mounted adjacent the 15 delivery end of the magazine and presenting its incising edge projecting into the path of descent of the articles whereby to engage the terminal article of the column, said blade effective when the terminal article is positively withdrawn from the column to incise the engaged portion thereof and thus permit its passage and to engage that article 20 next following in the column.

4. Means for releasably supporting a column of nested paper containers having 25 flanged tops, comprising a stop presenting an incising edge projecting into the path of withdrawing movement of the containers whereby to engage the flanged top of the

lowermost container in the column and support the column against accidental release, said blades effective when the lowermost container is grasped from below and positively withdrawn from the column to incise the flanged top of the said container and thus permit its passage therewith and immediately to engage the flanged top of the container next above in the column whereby again to support the column.

5. Means for releasably supporting a column of nested paper containers having flanged tops, comprising a pair of oppositely disposed stops each presenting an incising edge projecting constantly into the path of withdrawing movement of the containers, whereby to engage the flanged top of the lowermost container in the column and support the column against accidental release, said blades effective when the lowermost container is grasped from below and positively withdrawn from the column to incise the flanged top of said container and thus permit its passage therewith and immediately to engage the flanged top of the container next above in the column whereby again to support the column.

In testimony whereof I affix my signature.
THEODORE M. PRUDDEN.
